(57) **CLAIM**

The ornamental design for a laser sight and mount, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a perspective view of a laser sight and mount in accordance with my new design;

FIG. 2 is a rear, left, top perspective view thereof;

FIG. 3 is a top view thereof;

FIG. 4 is a front view thereof;

FIG. 5 is rear view thereof;

FIG. 6 is a bottom view thereof;

FIG. 7 is a left side view thereof;

FIG. 8 is a right side view thereof; and,

FIG. 9 is a front, right, bottom perspective view thereof.

All portions shown in broken lines are environmental and illustrative only and form no part of the claimed design.
